Richard E. Boiseau
INVENTOR

BY Victor J. Evans
ATTORNEY

UNITED STATES PATENT OFFICE

RICHARD E. BOISEAU, OF WASHINGTON, DISTRICT OF COLUMBIA

RECEPTACLE

Application filed September 19, 1929. Serial No. 393,768.

This invention relates to receptacles and more particularly to a receptacle which may be employed to receive waste paper, trash, soiled linen, etc., and which receptacle will 5 be of such construction that it will serve as a means for concealing from view cupboards, garbage cans, and other receptacles, so that such receptacles may be used in any home or office without their presence being apparent.

Another object of the invention is to provide a receptacle including a hollow cylindrical body and a bottom, in combination with means for supporting the bottom at 15 various elevations within the body so that such other receptacles as may be temporarily housed within the portion of the body of the waste paper and trash receptacle in the space below the bottom, may be accommodated, regardless of their height, by adjustment of the said bottom.

This invention also consists in certain other features of construction and in the combination and arrangement of the several 25 parts, to be hereinafter fully described, illustrated in the accompanying drawing and specifically pointed out in the appended claim.

In describing my invention in detail, reference will be had to the accompanying drawing wherein like characters denote like or corresponding parts throughout the several views, and in which:—

Figure 1 is a top plan view of the receptacle embodying the invention.

Figure 2 is a vertical diametric sectional view taken on the line 2—2 of Figure 1, looking in the direction indicated by the arrows.

Figure 3 is a perspective view of the bottom of the receptacle.

The receptacle proper is indicated, in the drawing, by the numeral 1 and may be made of wire, rattan, fibre, straw, wood, metal or any other material suitable for the purpose.

The body is of hollow cylindrical form, in itself and is open at both its upper and lower ends. However, in accordance with the present invention, a bottom indicated in general by the numeral 2 is provided, and this bottom may be made of sheet metal or any other

suitable material and is of the same diameter as the body 1, being circular in form and made of sheet metal or the like, and so formed that its upper side will be dished or of shallow conical form, as indicated by the numeral 3, for a purpose which will presently be made clear.

In order that the bottom 2 may be supported for adjustment to assume different positions of elevation within the body 1 of the receptacle proper, the said bottom 2 is formed at its periphery with a depending circumscribing flange 4 and, as will be observed by reference to Figure 2 of the drawing, this flange is adapted to fit relatively snugly within the body 1, so that the said bottom will be supported in a substantial manner. For the purpose of supporting the bottom 2 at different elevations, three or more vertical series of studs or lugs 5 are provided upon the inner surface of the body 1 at the lower portion thereof and the number of studs or lugs in each series and the spacing of the studs of all of the series is uniform. The flange 4 is formed at equi-distantly spaced points in its circumference, corresponding in number with the number of studs or lugs 5, with vertically extending slots 6, the slots opening at their lower ends thru the bottom 2 substantially at the line of juncture of the upper portion of the flange 4 with the periphery of the bottom. Each slot 6 is provided with a branch 7 extending at right angles to the slot and communicating with and extending from one side wall of the respective slot.

It will now be evident that the bottom 2 may be inserted into the body of the receptacle 1 and the slots 6 brought into registration with the uppermost studs or lugs 5 whereupon the bottom 2 may be slidably adjusted to assume any desired position of elevation within the said body, and at this time, corresponding studs or lugs of the several series, being in engagement in the slots 6 in the flange of the bottom, the bottom may be located so as to effect engagement of the studs or lugs in the branches 7 of the said slots, and at the same time, the bottom will be securely held and supported within the body 1 at the de-

sired elevation. Inasmuch as the upper ends of the slots 6 extend through the body 2 at their upper ends, substantially at the juncture of the upper edge of the flange 4 with the bottom 3, it will be possible to adjust the bottom within the body 1 by movement in either an upward direction or a downward direction, the engagement of the studs 5 in the branches 7 of the notches 6, constituting means whereby the bottom is held in different positions of adjustment.

In the embodiment shown in Figure 2 of the drawing, the numeral 8 indicates a cuspidor which is arranged upon the floor surface 15 upon which the lower end of the body 1 is disposed to rest and it will be understood by reference to this view, that any moisture which may accumulate upon the dished surface of the bottom 2 may be shifted by way 20 of a drain opening 9 formed centrally in the bottom 2, therefore if as illustrated, for example, in Figure 2 of the drawing, the receptacle 1 is employed for the temporary support of umbrellas, and the cuspidor is the object 25 which it is desired to conceal from view, the drain opening 9, being located at the center of the said body, will be positioned so as to discharge the accumulated moisture into the cuspidor or other receptacle.

30 It will be evident at this point, that the bottom 2 will be adjusted as low as practicable in consonance with the character of the receptacle 8, and that when it is desired to gain access to the receptacle 8, this may be 35 accomplished by merely lifting the body 1 from the position shown in Figure 2 and until its lower end has cleared the upper end of the receptacle 8.

From the foregoing description of the invention it will be seen that there is provided 40 a receptacle which may be employed in various ways to receive waste or soiled material without the receptacle 8 being exposed to view.

45 What I claim is:—

In a device of the class described, a hollow cylindrical body having a series of studs or lugs projections from its inner side, a bottom for the body having a central opening 50 therein surrounded by a drain spout opening, and means for supporting the bottom within the body of the receptacle at different elevations, in accordance with the depth of the receptacle to be housed within the space 55 within the said body below the said bottom, the said means comprising a flange depending from the bottom and provided with slots in which the projections or lugs are engageable.

60 In testimony whereof I affix my signature.
RICHARD E. BOISEAU.
